United States Patent

Des. 240,798
Patented Aug. 3, 1976

240,798

PACKAGING CONTAINER

Ernest L. Smith, Kansas City, Mo., assignor to Phillips
Petroleum Company, Bartlesville, Okla.

Filed Oct. 21, 1974, Ser. No. 516,482

Term of patent 14 years

Int. Cl. D9—01

U.S. Cl. D9—147

FIG. 1

FIG. 2

FIG. 3

FIG. 4

FIG. 5

FIG. 6

FIG. 7

FIG. 8

FIG. 1 is an elevational view of a packaging container, showing my new design;

FIG. 2 is a top plan view thereof, omitting the closure;

FIG. 3 is a perspective view thereof, with the closure in the recessed position;

FIG. 4 is a perspective view thereof, with the closure in the extended position;

FIG. 5 is an elevational view, showing a modified form of my new design;

FIG. 6 is a top plan view thereof, omitting the closure;

FIG. 7 is a perspective view with the closure in the recessed position; and

FIG. 8 is a perspective view thereof with the closure in the extended position.

I claim:

The ornamental design for a packaging container, as shown and described.
